UNITED STATES PATENT OFFICE.

OLE O. STORLE, OF BURLINGTON, WISCONSIN, ASSIGNOR TO BURLINGTON BRASS WORKS, OF BURLINGTON, WISCONSIN, A CORPORATION OF WISCONSIN.

VALVE.

SPECIFICATION forming part of Letters Patent No. 760,580, dated May 24, 1904.

Application filed April 9, 1903. Serial No. 151,734. (No model.)

To all whom it may concern:

Be it known that I, OLE O. STORLE, a citizen of the United States, residing at Burlington, in the county of Racine and State of Wisconsin, have invented certain new and useful Improvements in Valves, of which the following is a specification, reference being had to the accompanying drawings, forming a part thereof.

This invention relates more particularly to self-grinding valves of the class shown in United States Letters Patent No. 695,588, issued to me March 18, 1902.

The main objects of the present invention are to insure the turning of the valve-stem in the screw or movable member during the initial part of the operation in opening the valve, thereby insuring the grinding of the valve on its seat every time it is opened, to prevent leakage around the stem, and to admit of packing the stem when the valve is open and in operation, and generally to improve the construction and operation of valves of this class.

The invention consists in certain novel features of construction and in the peculiar arrangement and combinations of parts herein-after particularly described, and pointed out in the claims.

In the accompanying drawings like letters designate the same parts in the several figures.

Figure 1 is a vertical longitudinal section of a valve embodying my improvements. Fig. 2 is a horizontal section of the same on the line 22, Fig. 1. Fig. 3 is a detached view of the valve head and stem and of the screw or movable member associated therewith, the valve-head, screw, and a portion of the stem being shown in section. Fig. 4 is a horizontal section of the valve stem and screw on the line 44, Fig. 3; and Fig. 5 is a central longitudinal section of the screw, taken in a plane at right angles to that of Fig. 3.

In self-grinding valves of the kind shown in the above-mentioned Letters Patent the screw or movable member by which the valve head or disk is seated and unseated is apt to be turned with said head or disk by reason of the frictional engagement between the lower end of the screw and the upper side of the head or disk, these contacting surfaces being nearly of as great area as those of the engaging threads

on the screw and in the case, so that the valve head or disk is immediately moved away from its seat and prevented from grinding thereon when the valve-stem is turned in the direction to open the valve. It is, among other things, the purpose of my present construction to obviate this uncertainty in the operation of the valve without the use of a spring, which may be employed to hold the screw stationary during the initial movement of the valve head or disk in turning the stem to open the valve, but is not entirely satisfactory.

The valve-case, which may be, as shown, of a form similar to that of other valves in common use, consists of a body *a*, provided with a valve-seat *b*, and a cap *c*, threaded in an opening in the body coaxial with the valve-seat. The cap *c* has an externally-threaded neck *d* at its upper or outer end, on which a nut or gland *e* is fitted to form a stuffing-box around the valve-stem. A plain bore is made through the neck *d* and nut or gland *e* coaxial with the valve-seat and cap *c* for the passage of the valve-stem through the case, said neck forming a bearing for said stem.

f is an externally-threaded recessed screw having a circular hole through its upper end. It is fitted to engage with an internal screw-thread in the cap *c* and is formed, as shown in Figs. 4 and 5, on opposite sides with openings *g* and inwardly-projecting lugs or abutments *h*.

i is a cylindrical valve-stem formed or provided at its lower or inner end with a valve head or disk *j* and between its ends with a beveled shoulder or valve-face *k*. Between the valve-head *j* and the shoulder or valve-face *k* the enlarged portion of said stem is fitted to turn in the screw *f*, in which it is loosely held by a cross-bar *l*, passing through the openings *g* in said screw and a transverse opening or recess through said stem, as shown in Fig. 3. The valve-stem is beveled or rounded at the bottom and preferably, also, at the top of said transverse opening or recess to present central pivot-bearings to the opposing faces of the bar *l*, and thus facilitate the turning of the valve-stem in the screw *f*. The transverse opening or recess through the valve stem is made flaring at its ends, or wider

than the cross-bar *l*, as shown in Fig. 2, to permit a considerable range of movement to the valve stem and disk independently of the screw *f*; but this movement is limited by 5 wings or projections *m*, formed on opposite sides of the valve-stem and adapted to engage with the lugs or abutments *h* in the screw *f*.

The upper or outer end of the cap *c* around the hole or bore through the neck *d* constitutes 10 a seat for the shoulder or valve-face *k*, with which it forms a tight closure, preventing leakage around the stem when the valve is opened to the fullest extent.

The operation of my improved valve may 15 be explained as follows: In closing the valve the stem is turned to the right, first taking up the lost motion between the wings *m* on the valve-stem and the lugs *h* in the screw *f*, which is then turned with said stem in engagement 20 with the screw-thread in the cap *c*, thereby moving the valve head or disk *j* down against its seat. In opening the valve the initial movement of the stem when turned in the reverse direction does not affect the screw 25 *f*, the central pivot-bearing in the lower side of the transverse recess in the valve-stem turning freely against the under side of the cross-bar *l* until the lost motion or space between the wings *m* and the lugs *h* is taken up. 30 The screw *f* being then turned, with the valve-stem in engagement with the internal screw-thread of the cap *c*, unseats the valve-head *j*. Thus in the initial movement of the valve-stem to open the valve the valve-head is turned 35 upon its seat with whatever pressure or force is exerted to close it, and a true fit between the valve face and seat is produced and maintained. When the valve is opened to the fullest extent, so as to carry the shoulder or 40 valve-face *k* against its seat in the upper end of the cap *c*, the same action will take place with respect to said valve-face and its seat, when the valve-stem is turned in the reverse direction to close the valve, viz: The screw *f* 45 will remain stationary until the lost motion or space between the wings *m* and the lugs *h* is taken up, and the valve-face *k* will thus be turned against and ground true to its seat in the cap *c*.

50 Both the valve-seats are preferably formed, primarily, by two faces intersecting each other and forming angles more or less acute, which are presented toward the opposing beveled valve-faces and are thus more readily shaped 55 to conform thereto by the grinding movement of said valve-faces thereon.

Sufficient play or lost motion between the screw *f* and the valve-stem is provided for to enable the valve-faces to effectively remove 60 any scale or foreign matter adhering thereto or to the opposing valve-seats by the positive grinding movement of the valve-faces against their seats, as hereinbefore explained.

Various changes in minor details of construction and arrangement of parts may be 65 made without departing from the principle and intended scope of my invention.

I claim—

1. A valve comprising a movable member, a stem fitted to turn within said member, carrying a valve-head and formed with a recess in which is a central bearing, and a support in said recess for the stem, substantially as described. 70

2. A valve comprising a movable member, a stem fitted in said member to turn therein and formed with a transverse opening or recess, and a cross-bar lying within said recess and constituting a support for the stem, substantially as described. 75

80 3. A valve comprising a movable member, a stem fitted in said member to turn therein and formed with a transverse recess and a lateral projection, a cross-bar within said recess and constituting a support for the stem, and an 85 internal abutment within said movable member, and in the path of the projection on the stem, substantially as described.

4. A valve comprising a suitable case provided with valve-seats and a bearing for the valve-stem coaxial with said seats, a stem passing through and adapted to turn in said bearing and provided at one end with a valve-head and between its ends with an oppositely-directed valve-face, a movable member in 90 which said stem is adapted to turn a limited distance, lugs formed inside of the movable member, and projections formed on the valve-stem inside of the movable member and adapted to be brought into engagement with the 95 lugs inside of the movable member, substantially as described. 100

5. A valve comprising a movable member having an internal cross-bar, and a stem carrying a valve-head and fitted in said member 105 and formed with a recess to receive said cross-bar, said recess being wider at its ends than the cross-bar to permit a movement of the valve-stem and valve-head independently of the movable member, substantially as described. 110

6. A valve comprising a suitable case having a valve-seat and an internal screw-thread coaxial with said seat, a recessed screw engaging said screw-thread and provided with 115 an internal cross-bar, and a valve-head provided with a stem fitted to turn a limited distance in said screw and having a central pivot bearing opposed to said cross-bar, substantially as described. 120

In witness whereof I hereto affix my signature in presence of two witnesses.

OLE O. STORLE.
